CHARLES A. FERRELL, OF CLEVELAND, OHIO, ASSIGNOR OF ONE-HALF TO HARRY E. PAGE, OF CLEVELAND, OHIO.

INDUCTION-COIL.

1,223,947.

Specification of Letters Patent. Patented Apr. 21, 1917.

Application filed October 7, 1915. Serial No. 54,648.

To all whom it may concern:

Be it known that I, CHARLES A. FERRELL, a citizen of the United States, residing at Cleveland, in the county of Cuyahoga and 5 State of Ohio, have invented a certain new and useful Improvement in Induction-Coils, of which the following is a full, clear, and exact description, reference being had to the accompanying drawings.

10 This invention relates to induction coils and particularly to coils of a jump spark nature such as are used in the ignition of internal combustion engines, the transmission of wireless telegraph signals, and the 15 operation of high frequency apparatus; also in connection with certain types of transformers and in certain operations of physics and chemistry. In such devices as is well known, an interrupted or alternating current 20 on a primary of few turns is stepped up into an alternating current of greatly increased voltage by means of a secondary coil of many turns. Difficulty has sometimes been experienced from a burning out 25 or short circuiting or piercing of the secondary coil and it is the object of the present invention to overcome this condition in a simple and scientific manner, without impairing the operation of the coil.

30 For the production of an efficient induction coil it is necessary to concentrate the wire of the secondary winding into a small compass so as to include practically all or at least the greater part of it inside the 35 maximum field of the primary winding and magnetized core. This necessarily sets a limit upon the amount of insulation which can be used between adjacent layers and between adjacent turns in the same layer.

40 However, a second condition which is to be met is the fact that if an insulation of high specific inductive capacity be employed, the result is such increase of the condenser effect between successive layers (and even 45 between successive turns in the same layer) as markedly to change the character of the spark, reducing a spark which would otherwise be fat and hot into one which is lean and cold. This condenser effect is increased

by decreasing the distance between the turns 50 and layers, as is well known, which sets a lower limit to which the closeness of winding in the body of the coil can be carried; also the specific inductive capacity of the dielectric influences the condenser effect, 55 since experiment shows that a dielectric like mica or muslin-saturated-with-linseed-oil if used throughout the coil will produce a spark which is noisy and heatless, whereas a coil in which dry paper or some similar substance of low dielectric strength is used 60 between successive layers, and air (or some fibaceous like silk) is used between the adjacent turns will afford a spark which is noiseless and extremely hot; the same number of turns and the same general dimensions of coil being employed between the two cases. In fact the nature of the insulation upon the wire itself is important in 65 this regard, enameled wire being ineffective 70 for producing a hot spark because of the high specific inductive capacity of the insulation, but silk and cotton being fully satisfactory because of the smaller condenser action.

In a coil wound as above described, the 75 factor of safety of the insulation is obviously none too high between adjacent turns or between adjacent layers, although experience shows that breakdown, burning, or puncturing of the insulation is confined to 80 a point either at or closely adjacent to the free terminals of the secondary winding. In case both ends of the secondary winding are brought out in the form of free terminals, the observed failure of the insulation 85 may occur at either end; if one end of the secondary be grounded upon the primary, as is frequently done in high frequency work and engine ignition, there appears to be only one place where failure 90 of insulation need be anticipated, namely at the free terminal of the secondary coil or within a few turns therefrom. I have further discovered that during the operation 95 of a coil of this nature there is superimposed upon the ordinary and generally described secondary action a static surging effect wherein the amount of electricity involved

is extremely small but its electromotive force comparatively high—say several thousand volts. This effect, being in the nature of a wave motion, exhibits loops or points of high intensity and nodes or points of low intensity, and such a loop always occurs at or near the free terminal of the secondary coil. Under favorable conditions the effect of this small high potential static charge appears to be to form a path through the insulation and ionize the air along such path after which the true secondary discharge of larger quantity but lower potential is enabled to pass with its well known heating and disintegrating effect.

In order to overcome this danger of breakdown, or puncturing, I increase the insulation of the last layer or of the last few turns adjacent to each free turn on the secondary coil. In case the inner end of the secondary coil is grounded upon the primary as is usually the case in high frequency coils and in engine ignition, this increase of insulation is necessary only upon the outer layer. It is entirely a matter of convenience whether the excessive insulation be applied to the entire final layer or only to the few turns at the extreme end thereof, although the former construction is generally adopted as a matter of convenience. This additional insulation may either be a matter of quantity or of quality. Thus I may achieve the same by winding the last few turns in a more open manner than the remainder of the coil and over and around a larger amount of insulation of the same kind, or I may employ a different kind of insulation, such as mica or cloth saturated with linseed oil, since the condenser action consequent upon the higher dielectric strength through this small region is found not to impede the production of a hot discharge.

In the drawings accompanying and forming a part of this application wherein I have illustrated certain embodiments of my invention, Figure 1 is a partly diagrammatic and partly sectional view of an induction coil showing my improvements applied thereto; Fig. 2 is a similar view of a different type of secondary winding constructed in accordance with my invention; Fig. 3 is a view similar to Fig. 2 showing a modified form of secondary winding; Fig. 4 illustrates that form of my invention wherein I employ insulating materials of varying specific inductive capacities; Fig. 5 illustrates a double ended coil constructed in accordance with one form of my invention; and Fig. 6 illustrates a variety of pancake winding having my improvements applied thereto.

Describing the parts by reference characters, first taking up Fig. 1, 1 represents conventionally the core of an induction coil pro-

vided with a primary winding 2 connected through an interrupter 3 with a battery or like source 4, a condenser 5 being connected around the interrupter, 6 represents the secondary coil which is wound in the form of a cylindrical spool containing a plurality of layers of fine wire as shown at 7, successive layers being insulated from each other by thin paper or like material. Preferably this paper is not impregnated with any wax, gum or the like since the effect of such impregnation would greatly increase the dielectric strength and therefore the condenser effect. In Fig. 1 I have shown one of the terminals at 8 as grounded upon the primary and the other at 9 as led freely away from the secondary as customary in high frequency and engine ignition practice. In this view I have shown the outermost layer 10 as separated from the layer beneath by an unusually large amount of insulation 11, and have shown the half dozen turns nearest the end spaced comparatively widely apart as shown at 12. In this embodiment the insulation at 11 is supposed to be of the same nature as that of the rest of the coil and similarly unimpregnated, although impregnated material may be used at this point within the scope of my invention; the requirement being an excess of some nature at this point.

In Fig. 2 I have shown a secondary coil removed from the primary and having both of its terminals free for separate connection. In this embodiment the initial turns of the first layer of the secondary coil are spaced widely apart and surrounded on all sides by a comparatively large amount of insulation as shown at 15, and the final turns of the outside layer of the secondary coil are similarly spaced apart and abundantly insulated as illustrated at 16, the remaining turns of the initial and final layers as well as of all intermediate layers being crowded more closely together and separated by a much smaller amount of insulation as shown at 17. In each of the embodiments shown in Figs. 1 and 2 the insulation between adjacent layers is uniform, from one end of the coil to the other, the layers which carry the terminals being uniformly spaced away from the adjacent layers by the excess insulation. In Fig. 3 I have illustrated a third form of secondary coil in which one of the terminals 20 is arranged for connection to the primary winding while the other terminal 21 communicates with a few turns of wire 22 which are spaced more widely apart than the remaining turns of the coil 23, and are insulated from the remainder of the coil by an excess of insulation 24 which extends only as far as such widely spaced turns.

The preceding illustrations show coils that are thoroughly practical and which I have

actually made and used successfully, but the construction which I now prefer is that illustrated in Fig. 4 wherein 25 represents a cylindrical spool having an end 26 of suitable insulating material. Wire is wound thereon in layers as shown at 27, the wire being preferably cotton-covered, the adjacent turns of each layer being insulated chiefly by air. Adjacent layers are separated by unimpregnated paper and preferably very thin paper wound in several layers so as to obtain the benefit of the included air spaces. The whole coil is built in this manner until the final layer is reached whereupon an insulating layer 28 of higher insulating strength is employed, such as mica, oiled silk, or the like. Also the final turns adjacent the terminal 29 are preferably spaced apart somewhat more widely than the turns in the body of the coil. So far as the prevention of puncturing is concerned it is sufficient to confine this increased insulation to a short distance at the end of the layer, but for purposes of manufacturing convenience I generally make the whole layer uniform and this does not seriously impair the quality of the discharge.

In Fig. 5 I have shown a double ended coil wherein both termini of the secondary are led out. Each of the coils is preferably wound in the manner shown in Fig. 4; the inner ends being connected at 30. Of course, the direction of winding of the two coils must be so chosen that their inductive effects may be added together, and when so constructed the points 30 cause a node and not a loop, so that no puncturing need be apprehended at this point. In this instance I have shown only a portion of the outermost layer between the points 28 and the terminals 31—31 as provided with the excess insulation.

In Fig. 6 I have shown the simplest form of pancake winding, consisting of a spool 32 which may be of wood or some non-conductor, having therein a plurality of external circumferential grooves 33—33. Such a spool is wound merely by filling the grooves successively with insulated wire spun therein without any attempt at insulation excepting the cotton or silk coverings. In this case my invention is performed by including inside the outer layer of each terminal groove a thickness of mica or oiled silk as shown at 34, and preferably spacing the turns outside of this insulation slightly more widely.

While the same effect of obtaining freedom from breakdown could be obtained by winding all of the turns of the whole coil similarly spaced apart and similarly carefully insulated, such a construction would defeat the very purpose of the coil which is to produce a hot, high-potential, efficient

spark; since the comparatively great space which the coil would necessarily occupy in order to permit such uniform excess of insulation would greatly increase the wire resistance or copper loss and would also bring the outside turns of the coil so far from the influence of the magnetic field set up by the primary as greatly to decrease its efficiency. Also, as already explained this danger of breakdown would be overcome by using mica, oil silk, or the like for the insulation in the body of the coil as well as at the terminal layers, but this would impair the action of the coil by reason of the greater specific inductive capacity of the dielectric. By my invention, I avoid all condenser effect by employing an insulation of minimum dielectric strength, I retain a concentrated action by using the smallest practicable quantity of insulation, and finally achieve freedom from breakdown by reinforcing the weakest points, either by greater quantity or higher quality of insulation. It might be argued that a similar avoiding of puncturing would be attained by discovering one of the nodal points above mentioned and cutting back the terminal to that point. However this will be found to rearrange the whole wave motion, shifting the nodal points so that the terminal connection would still remain at a loop.

It will also be understood that the invention is equally applicable to high tension magneto windings and to all coils connected with pulsating or intermittent currents.

While I have described my invention at length and set forth the theory of operation so far as I have been able to discover the same, still I do not confine myself to the theories herein set forth but only to the methods, constructions, and combinations whereby the results specified are attained, and not specifically to these except as the same are definitely recited in the claims hereto annexed or rendered necessary by the prior state of the art.

Having thus described my invention, what I claim is:—

1. An induction coil secondary having the different layers of wire within its body separated by insulating material of low specific inductive capacity and having the turns adjacent each free terminal separated from the remainder of the coil by insulating material of higher specific inductive capacity.

2. An induction coil secondary having adjacent layers of wire in its body portion separated by non-impregnated paper and having a portion adjacent to the free terminals insulated by a layer of substantially the same thickness as the said paper layer and of a material of higher specific inductive capacity than that of paper whereby the outer turns are more effectively insulated

than the inner turns but are compacted together to the same extent.

3. A coil for electrical use comprising a plurality of layers of helically wound wire, the layers in the body of the coil being separated by thin sheets of dry paper and the terminal layers being insulated by sheets of impregnated material whereby the outer turns are more effectively insulated than the

inner turns but are compacted together to 10 the same extent.

In testimony whereof, I hereunto affix my signature in the presence of two witnesses.

CHARLES A. FERRELL.
